ELECTRON DISCHARGE DEVICE

Original Filed March 3, 1924

Inventor:
Albert W. Hull,
by *Charles V. Tullar*
His Attorney.

UNITED STATES PATENT OFFICE

ALBERT W. HULL, OF SCHENECTADY, NEW YORK, ASSIGNOR TO GENERAL ELECTRIC COMPANY, A CORPORATION OF NEW YORK

ELECTRON DISCHARGE DEVICE

Original application filed March 3, 1924, Serial No. 696,665. Divided and this application filed August 22, 1928. Serial No. 301,336. Renewed August 3, 1931.

My present invention relates to electron discharge devices, and more particularly to devices of the four electrode type. This application is a division of my prior application Serial No. 696,665, filed March 3, 1924 upon which Patent 1,855,885 was issued April 26, 1932.

It is well known that in the usual three-electrode, electron discharge device there is an appreciable capacity between the grid and anode, and that by reason of this capacity the amplifying effect of the device, particularly at high frequencies, may be greatly reduced. In the operation of such devices there is also a marked tendency for the production of undesired high frequency oscillations by reason of this capacity.

In my Patent 1,610,783, issued December 14, 1926, I have indicated and claimed certain circuit arrangements whereby this difficulty may be overcome. I have in that patent shown a fourth grid electrode interposed between the control grid and the anode. By proper circuit connections this electrode serves to screen the grid and plate, and thereby eliminate capacity effect between these two electrodes. As a result the degree of amplification obtained with a single device may be greatly increased and the tendency for the production of high frequency oscillations is reduced.

I have found, however, that by proper construction of the electron discharge device an additional advantage may be obtained over that which may be obtained if the extra grid is located and constructed in the usual manner. If the screening grid is made of the same length as the control grid there will still be a remaining capacity effect between the control grid and the anode due to the leakage of electrostatic lines of force around the end of the screening grid. Also if the leads by which current is supplied to the different electrodes are parallel to one another there will be a sufficient capacity between the leads of the anode and control grid to materially affect the operation of the device.

The object of my present invention is to overcome this disadvantage and provide a construction in which the capacity effect be-

tween the control grid and anode is reduced to such a degree that it produces substantially no effect in the operation of the device. This object may be attained in various ways. One expedient which assists materially in producing this result is to provide a screening grid which is materially longer than the control grid and anode and extends an appreciable distance beyond both ends of the control grid and anode, or is otherwise arranged to effectively intercept the electrostatic lines of force which spread out beyond the ends of the control grid and anode. To avoid the capacity effect between the leads the lead for the control grid is preferably brought out of the evacuated receptacle at the opposite end from the anode lead. The expedients which I have mentioned are effective in reducing the capacity effect to a low enough value to enable satisfactory amplification to be obtained in some cases. In other cases, however, particularly where the frequencies to be amplified are very high there may be still enough remaining capacity effect to interfere with the desired operation of the device. Such capacity effect may be due to the stray electrostatic lines extending from the anode to the control grid and particularly to the lead from the control grid in other than straight or short paths.

A more specific object of my invention is to provide means for still further reducing the capacity effect by providing means for intercepting these stray lines. This object may be attained by the provision of a conductive screen surrounding all of the electrodes and conductively connected to the screening grid.

The novel features which I believe to be characteristic of my invention are set forth with particularity in the appended claims. My invention itself, however, will best be understood by reference to the following description taken in connection with the accompanying drawing in which the single figure shows an elevation of a device constructed in accordance with my invention.

I have indicated in the drawing an evacuated receptacle 1 in which are mounted a V-shaped filamentary cathode 2 and a control

grid 3, the tube and anode being shown as broken away so that portions of the cathode and control grid may be seen, an anode 4, and a screening grid 5, which is interposed 5 between the control grid and anode. The current for the cathode is supplied through the stem 6 by means of the leading-in conductors 7 and 8. The end of the cathode remote from the stem is supported by means of a spring 10 9 secured to the end of a supporting rod 10. The opposite end of the supporting rod 10 is embedded in a block 11 of insulating material, this block of insulating material being secured to supports 12 and 13, the opposite ends of which are embedded in the 15 stem 6. The screening grid 5 is secured by the transverse supports 14 to supporting members 12 and 13. The supporting member 12 extends through the stem 6 and forms a 20 continuation of the leading-in conductor 15 by which current is supplied to the screening grid. The supports 16 and 17 of the control grid are also embedded in the block 11 of insulating material, and support 17 is ex- 25 tended through the block and connected to the leading-in conductor 18 whereby current is supplied to the control grid. The anode is supported from the stem 6 by means of supports 19 and 20, and support 20 is connected 30 to leading-in conductor 21 which serves to supply current to the anode.

It will be noted that in the construction described all of the electrodes are coaxial and the screening grid extends an appreciable 35 distance beyond both ends of the control grid and anode 4, thereby serving to intercept electrostatic lines of force extending beyond the ends of these electrodes. The control grid lead is also brought out of the receptacle at 40 the opposite end from the anode lead so that there is no unscreened capacity between the two leads. This construction permits the use of the usual four-electrode base 22 at one end of the device with any simple form of 45 terminal at the opposite end for the control grid lead.

As an additional screening means a conductive screen surrounding all of the electrodes is provided. In the modification illustrated 50 this screen takes the form of a metallic coating 27 covering the inner wall of the receptacle 1, and this metallic coating is connected to conductor 28 which in turn is secured to the support 12 of the screening 55 grid. The metallic coating, if desired, may cover the entire interior of receptacle 1. This coating serves to intercept electrostatic lines of force from the anode, which might pass around the end of the screening grid to the 60 control grid, and to the lead for the control grid, and thus serves as an additional element for screening the control grid from the anode.

By the means which I have described, any 65 capacity effect between anode and control

grid may be so effectively eliminated as to be entirely inappreciable. As previously constructed the screening grids have only been effective in intercepting electrostatic lines extending directly between the anode and control grid. I have however in the arrangement shown provided means which are effective in intercepting not only the electrostatic lines extending directly between anode and control grid, but also electrostatic lines extending in curved paths between the two electrodes as well as electrostatic lines extending from the anode to the lead for the control grid, or from the anode lead to the lead from the control 70 grid. 75

What I claim as new and desire to secure by Letters Patent of the United States is:

1. The combination in an electron discharge device of a receptacle containing an electron emitting cathode, an anode and a control grid, a screening system comprising a portion interposed between the anode and control grid and another portion which surrounds all of the electrodes for intercepting electrostatic lines of force extending from the anode. 80

2. The combination in an electron discharge device of a receptacle containing an electron emitting cathode, an anode, a control grid and a screening grid, interposed between the anode and control grid, and a metallic shield within said receptacle surrounding all of said electrodes and connected to the screening grid. 90

3. The combination in an electron discharge device of a receptacle containing an electron emitting cathode, an anode and a control grid and a shielding means adapted to intercept substantially all electrostatic lines of force extending from the anode toward the grid, said means including a screening grid interposed between the anode and control grid and a coating on the wall of said receptacle which surrounds all of said electrodes, said coating being adapted to have a definite potential impressed thereon. 100

4. The combination in an electron discharge device of an electron emitting cathode, an anode and a control grid and screening means within the device for eliminating substantially all of the effect of capacity coupling between the control grid and the anode, said screening means comprising a second grid interposed between the anode and control grid and conductive means surrounding said anode and electrically connected to said second grid and together with said second grid constituting an intercepting screen which effectively intercepts substantially all electrostatic lines of force extending from the anode toward the grid both in straight lines and otherwise than in straight lines. 110

5. The combination in an electron discharge device of an electron emitting cathode, an anode and a control grid and screening means within the device, said screening means 115

- comprising a screening grid interposed between the anode and control grid and coaxial therewith and of at least as great a length as the longer of the two and additional means
5 electrically connected to said screening grid for intercepting electrostatic lines of force extending from the anode toward the grid in other than straight lines.
6. The combination in an electron dis-
10 charge device of an electron emitting cathode, an anode and a control grid, the leads of the anode and control grid being widely spaced to avoid capacity coupling between them, and screening means within the device, said
15 screening means comprising a screening grid interposed between the anode and control grid and coaxial therewith and of at least as great a length as the longer of the two and additional means electrically connected to said
20 screening grid for intercepting electrostatic lines of force extending from the anode toward the grid in other than straight lines.

7. The combination in an electron dis-
charge device of an electron emitting cathode,
25 an anode and a control grid, and shielding means for intercepting the electrostatic lines of force extending between the electrodes comprising a shielding element interposed between the anode and control grid and an ad-
30 ditional shielding element surrounding the anode, and connected to the first shielding element.

In witness whereof, I have hereunto set my hand this 21st day of August, 1928.

35
